UNITED STATES PATENT OFFICE.

PETER MONAHAN, OF PATERSON, NEW JERSEY, ASSIGNOR TO HARRY R. SINCLAIR, OF WORCESTER, MASSACHUSETTS.

STRAP WRENCH.

1,294,515.

Specification of Letters Patent. Patented Feb. 18, 1919.

Application filed January 10, 1916. Serial No. 71,287.

To all whom it may concern:

Be it known that I, PETER MONAHAN, a citizen of the United States, residing at Paterson, county of Passaic, State of New Jersey, have invented an Improvement in Strap Wrenches, of which the following description, in connection with the accompanying drawing, is a specification, like characters on the drawing representing like parts.

This invention relates to strap wrenches and has for its object to provide a novel construction by which the life of the strap can be lengthened.

In using a strap wrench, the wear on the strap where it encircles the pipe and has the gripping engagement with the nose of the wrench all comes on one portion of the strap, and as a result, the strap becomes so worn at this point after a comparatively short term of use that it is liable to break.

I have provided herein a construction wherein the strap may be shifted relative to the handle so that the wear will come on different portions of the strap. With my invention, therefore, the strap may be used in one position until it begins to wear, and then its position may be shifted so that the wear will come on another unworn spot of the strap, and when the strap begins to show signs of wear again its position may be still further shifted relative to the handle, thus bringing a fresh, unworn spot into use. With my invention it is possible to use a strap much longer than can be done where the position of the strap cannot be shifted relative to the handle.

In order to give an understanding of my invention I have illustrated in the drawings a selected embodiment thereof which will now be described after which the novel features will be pointed out in the appended claim.

In the drawings, Figure 1 is a side view of a wrench embodying my invention;

Fig. 2 is a section on the line $x-x$, Fig. 1, looking in the direction of arrow y .

1 indicates the handle or body portion of a strap wrench, and 2 is the strap element which is adapted to encircle and grip the pipe 3. In the construction herein shown, one end of the strap 2 is fastened to a U-shaped shackle or clip 4 which is pivotally connected to the handle 1, this being accomplished by looping the end of the strap

about the shackle, as shown at 5, and then sewing or otherwise fastening the end 6 of the loop to the body of the strap.

The handle 1 is provided at its end with the gripping or biting nose 8 which is formed with the convexed strap-engaging surface 9. In using the device the strap 2 is passed about the pipe 3 which is to be turned or gripped, and the end 7 of the strap is inserted between the nose 8 and the body of the strap and then inserted through the U-shaped shackle 4, as shown in Fig. 1, the strap being drawn up tightly about the pipe 3. When the strap is thus arranged and the handle 1 is moved downwardly Fig. 1, the portion 10 of the strap will be firmly gripped between the nose 8 and the body portion of the strap and the strap will be tightened about the pipe 3, thus causing the strap to grip the pipe sufficiently so as to turn the latter.

The device as thus far described is one which is more or less commonly used and is not novel with me. In using a strap wrench of this type the greatest strain comes on the portion of the strap which is acted upon by the nose 8, and both plies of the strap are subjected to said strain. These straps 2 are usually made of heavy woven fabric, and experience has shown that after a comparatively short use, the strain on the fabric of the strap where it is bent over the nose 8 causes the strap to wear and tends to break the threads of the fabric at this point. If the wrench is used after such wear begins to show, the strap will very soon be unfit for further service.

I have provided a construction wherein the position of the strap can be adjusted relative to the handle 1 so that different portions of the strap may be brought into position to receive the strain incident to the use of the strap. I accomplish this by providing a construction wherein the shackle 4 may be fastened to the handle 1 in different positions. The shackle is shown as pivotally secured to the handle 1 by means of a bolt 12 which extends through eyes 13 at the ends of the shackle and through an aperture in the handle 1. I have herein provided for adjusting the strap relative to the handle by making the latter with a plurality of apertures 11 into any one of which the bolt 12 of the shackle 4 may be secured. When the bolt 12 of the shackle is placed

in the left-hand hole 11, a different portion of the strap 2 will be subjected to the strain incident to passing around the nose 8 than when the shackle is secured in either one of the other holes 11. My invention, therefore, provides a construction by which the wear and strain on the strap can be distributed over a considerable length thereof, thus materially lengthening the life of the strap.

In using the device the shackle 4 will be pivotally mounted in one of the apertures 11 and the wrench will be used until the portion of the strap that is bent over the nose 8 begins to show some signs of wear. Then the shackle may be adjusted to another one of the holes 11 which will bring a fresh portion of the strap in position to be engaged by the nose 8, and when this fresh portion begins to show signs of wear the shackle may be still further adjusted.

I claim:

In a strap wrench, the combination with a handle having a pointed clamping nose at one end and provided with a plurality of transverse apertures situated at different distances from the nose, of a shackle, means to pivotally secure said shackle into any one of said apertures, and a strap secured at one end to said shackle and adapted to be passed around the nose and then around a pipe and to have the other end thereof inserted between the first-named end and said nose, the adjustment of the shackle into different apertures providing for bringing different portions of the end of the strap which is secured to the shackle into position to receive the strain due to bending said portion of the strap over the pointed nose.

In testimony whereof, I have signed my name to this specification.

PETER MONAHAN.
